UNITED STATES PATENT OFFICE.

THOMAS B. DIXCY, OF EAST ORANGE, NEW JERSEY.

DESIGN FOR A BALLOON.

SPECIFICATION forming part of Design No. 21,874, dated September 27, 1892.

Application filed July 15, 1892. Serial No. 440,162. Term of patent 3½ years.

To all whom it may concern:

Be it known that I, THOMAS B. DIXCY, a citizen of the United States, residing at East Orange, Essex county, New Jersey, have invented a new and original Design for a Balloon, fully described and represented in the following specification and the accompanying drawings, forming a part of the same.

This design consists in the shape for a toy balloon shown in the annexed drawings, in which—

Figure 1 is an elevation slightly in perspective, and Fig. 2 a central vertical section, of an article embodying my design.

The article resembles a hat in shape, of which *a* is the body, and *b* the brim. *c* is the bottom of the balloon, which is encircled by the brim and is of conical shape, projected downwardly, and provided with the central aperture *d*.

The essential features of the design are the body *a* and brim *b*, together resembling a hat, and the downwardly-projecting conical perforated bottom *c*, arranged as above described.

Having thus set forth the nature of the design, what I claim herein is—

The design for a balloon herein shown and described, having the shape of a hat body *a* and brim *b*, with downwardly-projecting conical perforated bottom *c*, substantially as herein set forth.

In testimony whereof I have hereunto set my hand in the presence of two subscribing witnesses.

THOMAS B. DIXCY.

Witnesses:

THOMAS S. CRANE,
JOSEPH M. STOUGHTON.
